VICTOR CONTINSOUZA AND MAURICE BAPTISTE COMBES, OF PARIS, FRANCE

CINEMATOGRAPH WITH CONTINUOUS FEED OF THE FILM

Application filed May 28, 1926, Serial No. 112,361, and in France June 17, 1925.

The invention of the slot of a continuous image feed cinematograph is to determine, through its lower and upper edges, the junction between the two image portions juxtaposed on the screen. When the height of the slot is equal to the advance or movement of the film between one image and the next 5 the lower edge and upper edge are projected on the screen along one and the same geometric line and the two portions of the projected image are properly juxtaposed.

If the advance of the film is less than the height of the aperture the two portions of the image overlap one another in the vicinity 15 of the junction, which betrays itself by the projection of a bright transverse band upon the screen.

If, on the contrary, the pitch of the film is greater than the height of the aperture, 20 the projected image is barred or marked transversely with a dark band.

In either case, the band travels vertically upon the screen during the working of the apparatus and if this band is a definite width 25 its passage may become perceptible and interfere with the projection. Now the pitch of the film being always more or less variable, the said band (dark or light) will inevitably appear in the course of the projection of the 30 film and will exert its unfavourable influence.

According to the present invention, this disadvantage is obviated by making the height of the projection aperture variable in order to allow of maintaining it constantly 35 equal to the pitch of the film.

The control of the mechanism for adjusting the aperture is preferably co-ordinated with that of the device by which the fixity of the image is obtained in spite of the variations of pitch of the film, this coordination being effected in such a way as to allow of 40 correcting simultaneously and by the operation of a single member all the consequences of the fluctuations of the pitch.

By way of example there is represented 45 on the annexed drawing form of construction of a device arranged with a view to regulating the height of the projection aperture.

Figure 1 is a front elevation.

Figure 2 a section of Figure 1 upon a vertical plane 2—2.

Figure 3, a section of the same Figure 1 upon a horizontal plane 3—3 of Fig. 2.

Fig. 4 is a diagram showing the assemblage 55 of a continuous feed apparatus having a crown of lenses.

Fig. 5 is a perspective view showing the assemblage of a continuous feed apparatus having a crown of lenses.

In these figures, 1 designates the gate or runway in which the projection aperture 2 is formed. The edges of this gate form grooves in which a plate 3 is adapted to slide. This plate carries a lug 4 which is engaged in the forked end 5a of a lever 5 pivoted at 6 on the frame of the apparatus.

By operating the lever 5 it is thus possible to vary the height of the projection aperture in order to adjust it to the pitch of the 70 film.

Cinematographs with continuous movement of the film generally include a device for correcting the consequences of the irregularity of the pitch of the film, other than that 75 to which the invention more especially relates.

In certain cinematographs having continuous movement of film, this movement is compensated by a series of movable lenses 7 80 each accompanying one image of the film F during the period of projection of this image (Fig. 4).

It is necessary to provide in general, means for displacing the lens support in the direction of the axis of projection for the purpose of varying the distance of these lenses with respect to the film F, for reestablishing the fixed relation of the projected image although the rate of movement of the film varies.

In combining the control of the displacement of the support of the lenses 7 with the control mechanism of the movable blade 3, it becomes possible to maintain the fixed relation of the projected image, altogether eliminating the movable band, obscure or brilliant, which is produced on the screen whenever the rate of movement of the film varies without corresponding compensation of the image height.

For example, in Figure 5, the control lever 5 of the movable lever is actuated, in turning, by means of the knob 8, a shaft 9 which carries an eccentric 9', the strap of which is connected to the control lever 5 by a rod 10. On this same shaft 9 is mounted a drum 11 provided with a groove formed as a cam and with which engages the extremity of a lever 12 pivoted at 12' on a fixed axis. This lever 10 forms at its other end, a fork 12'' which embraces a collar 7' having a circular channel, said collar being keyed to a shaft 7'' which carries the crown of lens 7. This shaft is capable of sliding in its bearings. On the shaft 7'' is mounted by means of a long spline, a helicoidal pinion 13 in mesh with a similar pinion 13', carried by means of a shaft 14 which shaft also carries the toothed drum 14' entraining the film, which last-named shaft 20 is provided with a hand crank 14.'' The objective is indicated by the reference character O.

It is apparent that thus may be obtained the desired fixity of the projected image and the suppression of the dark or bright band barring the projected image.

It is quite evident that the invention is not limited to the shapes and the details of construction described above purely by way of example but may give rise to any modification based upon the same principle.

Thus, if desired, the two lips of the aperture might be made movable.

What we claim is:

35 In a cinematograph with continuously moving film, the combination with an optical system for the compensation of the travel of the film, a projecting aperture near the film, means adapted for varying the dimension of the said aperture in the direction of travel of the film, means adapted for displacing the said optical system along the projecting axis and connecting means between those two regulating means, for the purpose described.

45 In testimony whereof we have signed our names to this specification.

VICTOR CONTINSOUZA.

MAURICE BAPTISTE COMBES.
